COLONIC IRRIGATOR

Harry Lazarus, New York, N. Y.

Application July 25, 1938, Serial No. 221,176

3 Claims. (Cl. 128—227)

This invention relates to a colonic irrigator and more particularly it has reference to a device for controlling the flow of irrigating fluid and admitting additional treating agents to the colon.

It has long been recognized that irrigation of the large intestine is superior to treatment with cathartics and laxatives in cases of constipation. It has also been recognized that a simple enema consisting of filling the colon with water and permitting the emission of the contents does not give satisfactory results since the colon wall comprises a number of pockets in which fecal matter and gases readily accumulate to the acute discomfort of the patient. Such deposits can only be dislodged by repeated flushing accompanied by turbulence of the injected fluid. Another feature that has been the cause of improper irrigation is the configuration of the large intestine. Due to the sharp curvatures of the sigmoid portion, short nozzles or rectal tubes give flushing of the lower part of the descending colon only. In order that the benefits of an enema will reach all parts of the bowel it is necessary that a long nozzle, preferably of rubber or similar resilient material, be used.

Repeated insertions of such long nozzles results in irritation of the rectum and it has been proposed to use a device permitting the nozzle to remain in the patient's body throughout the period of treatment and obtain the desired injection of fluid and drainage by operation of suitable valves. Devices for accomplishing this result are now known but they generally involve complex and expensive equipment which cannot be satisfactorily operated by any but a trained expert.

I have devised a simple, yet unusually effective control mechanism for the administration of colonic irrigation which may be operated at its best efficiency by any normally intelligent person. The device permits close control and complete knowledge of the effectiveness of the treatment in an apparatus of relatively small size.

The present invention contemplates the provision of a colonic irrigator which will permit successive irrigations of the bowel tract without removal of the rectal tube or nozzle. A further feature of my device is the provision of means whereby the nature of the effluent matter resulting from the treatment may be accurately determined. The device also provides means for causing substantial turbulence of the irrigating fluid within the colon. To enable the operator to inject a soothing material such as an oil as the final stage of the treatment the device includes

a liquid reservoir from which such soothing material may be injected into the colon.

Other objects and advantages of this invention will be apparent from the following description considered in connection with the attached drawing illustrative of one embodiment of the invention wherein:

Fig. 1 represents a plan view of my device;

Fig. 2 is a sectional view on line 2—2 of Fig. 1; and

Fig. 3 is a detail view of the three-way plug valve employed to control the admission of air to the colon of the patient under treatment.

As illustrated in Fig. 1, the device comprises a hollow body portion 10 formed with a relatively large chamber 11 having ports communicating by means of channels through the body with inlet nipple 12, outlet nipple 13 and a nipple 14 for attachment of a rectal tube of conventional design. The flow of liquid through the channels is controlled by suitable valves, such as plug valves 15, 16 and 17. An additional channel is also formed in the body to communicate with the rectal tube channel by means of port 18 at a point intermediate nipple 14 and valve 17. As shown in the drawing this channel is formed to communicate with the outer atmosphere at port 19 and is extended through the center of an air tube nipple 20. These three openings are controlled by three-way valve 21 whereby any two of the three openings may be operatively connected to provide for flow of air therebetween. An air tube 22 of rubber or other suitable material is fitted at one end to nipple 20 and a suitable bulb 23 for causing flow of air through said tube is attached to the other end thereof.

The body portion 10 may be formed of any suitable material such as metal, glass or resinous substances which will be unaffected by the fluids within chamber 11 and will not result in contamination of such fluids and is readily constructed by casting or similar methods. The valves are preferably formed of the same material and in the same manner as the body portion. For light weight construction I prefer to make the device of an aluminum alloy by casting in a mold after the manner of present casting technique.

An important feature of this invention is the provision of means whereby an oil or a medicant may be introduced into the chamber 11 without disconnecting any of the tubes which are attached to the nipples 12, 13 and 14 in normal operation. This means is preferably so constructed that the nature of liquid flowing through chamber 11 may be accurately observed by the operator

and comprises a cover 24 removably secured to a flange 25 on the body portion 10. In the preferred embodiment of the invention the cover is attached to the flange by threads in the manner shown and a rubber gasket 26 is placed between the cover and the flange in order to make the joint water tight. Projecting knobs 27 are formed on the periphery of the cover to aid in removal thereof or wings, corrugations or the like 10 are provided to make it possible to rotate the cover without difficulty even though it be covered with oil or other slippery material. A sight glass 28 is set in cover 24 and preferably the glass is a concave lens in order that the material passing through the chamber will be seen by the operator as magnified to allow very accurate determination of its nature.

It will be seen that operation of the present device is very simple as compared with that of 20 prior apparatus adapted to the same purpose. A reservoir of suitable irrigation fluid is attached by a tube to nipple 12, while a second tube leading into a waste receptacle is attached to nipple 13. A rectal tube, preferably of rubber and having 25 openings along the side near the tip thereof is attached to nipple 14. Valve 21 is rotated to a position that will prevent flow of liquid through port 18 and valves 16 and 17 are closed. The tip of the rectal tube is then inserted in the rectum of the patient to a sufficient distance that the openings therein will be at least at the sigmoid region. When the tube is in place valve 17 is opened until a suitable amount of irrigating fluid has been injected into the colon of the patient, whereupon valve 17 is closed. It is apparent that the pressure of the irrigating fluid supplied to the rectal tube may be controlled by manipulation of valves 15 and 17.

It will be noted that when valve 21 is in a 40 position to inhibit flow through port 18, the opening in nipple 20 communicates with the atmosphere, whereby the bulb 23 is filled with air at atmospheric pressure. While the colon of the patient is filled with irrigating fluid, valve 45 21 is rotated until port 19 is closed and there is a clear channel from nipple 20 to port 18. The bulb is then pressed, forcing air through port 18, nipple 14 and the rectal tube into the colon of the patient. This operation results in ebullition 50 of air through the liquid in the colon and causes considerable turbulence thereof. The effect of forcing air through the rectal tube is threefold, first, the turbulence created in the fluid within the colon results in very efficient 55 washing of the colon walls and tends to dislodge fecal matter that has accumulated thereon and in the pockets thereof; second, the turbulence dislodges gases that may have accumulated in the said pockets; and third, the air tends to displace solid particles that may have become lodged 60 in the openings of the rectal tube, thereby impairing its efficiency.

The forcing of air through the rectal tube is repeated as many times as are found desirable 65 by rotating valve 21 to permit filling of bulb 23, again rotating the valve to close port 19 and pressing the bulb.

Valve 15 is then closed and valves 16 and 17 are 70 opened to permit flow of fluid from the colon to a waste receptacle or sewer through nipple 13. After the irrigating fluid is removed valve 16 is closed, valve 15 is opened and the operation repeated. This cycle may be repeated as many 75 times as are necessary to completely cleanse the colon and the degree of cleanliness achieved is

determined by the nature of the fluid passing through chamber 11 as viewed through sight glass 28.

When it is found that the effluent liquid is clear, the valve 17 is closed and the chamber 11 is 5 drained by opening valve 16 and removing cover 24. According to the preferred method of treatment, valve 16 is then closed and the chamber 11 is filled with a mild oil, preferably a vegetable oil such as olive oil, sesame oil or coconut oil, to 10 which a few drops of eucalyptus oil may be added. I have found that olive oil gives best results, but material benefits may be obtained through the use of any bland oil which will have a sooth- 15 ing and lubricating effect on the colon wall.

With the chamber 11 full of oil, valves 15 and 17 are opened and the pressure of fluid from the reservoir will force the oil through nipple 14 and the rectal tube into the colon of the patient. It will be noted that the opening from chamber 11 20 which communicates with nipple 14 is relatively high in the wall of said chamber and the oil, being lighter than the water generally employed as the irrigating fluid, will be forced out of the chamber first. While the colon contains oil it is well to massage the abdomen vigorously to insure penetration of oil to all the folds and pock- 25 ets of the colon.

For efficient operation, the position of the openings from chamber 11 to the channels communicating with nipples 12, 13 and 14 should be carefully placed. The inlet opening communicating with inlet nipple 12 should be spaced slightly above the bottom of the chamber and the opening for nipple 14 should be placed at a point near the top of the chamber in order that oil will be expelled through the rectal tube when water is admitted to the oil filled chamber. The outlet opening, communicating with outlet nipple 13 is preferably so placed that it opens onto the 40 floor of the chamber in order that proper drainage may be obtained.

Although the irrigating fluid used forms no part of the present invention, it is believed that plain water is most suitable but solutions may be employed if desired. Thus the fluid used in this device may be a water solution of sodium bicarbonate, common table salt or sodium permanganate made up in the usual manner.

It has been found by actual tests that colonic irrigation conducted in the manner set forth herein results in an intense feeling of health and well being. Prior to this invention such treatments have been difficult to conduct and self-treatment by the ordinary individual having no training in connection with the apparatus heretofore provided for that purpose has been practically impossible. The present device is easily operated by any normal person and it is only necessary that he be provided with relatively 55 simple instructions as to the procedure to be followed.

Even those persons who have been trained to conduct treatments of the present type find that use of the apparatus provided by this invention 60 simplifies their work and renders control of the treatment remarkably accurate.

I claim:

1. A device for use in colonic irrigation comprising an enclosed chamber defined by upper, 70 lower and side walls, valve controlled means to permit flow of irrigating fluid to said chamber, valve controlled means to permit the flow of waste from said chamber, means comprising a channel through a side wall of said chamber to 75

3. A device for use in colonic irrigation comprising upper, lower and side walls defining an enclosed chamber, three channels in side walls of said chamber, a valve in each of said channels to control flow of fluid therethrough, means at the end of each of said channels remote from said chamber for connecting a rubber tube in operative relation thereto and means for admitting air under pressure to one of said channels intermediate the said valve therein and the said means at the end thereof remote from said chamber.

2. A device for use in colonic irrigation comprising upper, lower and side walls defining an enclosed chamber, three channels in side walls of said chamber, a valve in each of said channels to control flow of fluid therethrough, means at the end of each of said channels remote from said chamber for connecting a rubber tube in operative relation thereto and means for admitting air under pressure to one of said channels intermediate the said valve therein and the said means at the end thereof remote from said chamber.

3. A device for use in colonic irrigation comprising upper, lower and side walls defining an enclosed chamber, three channels in side walls of said chamber, a valve in each of said channels to control flow of fluid therethrough, means at the end of each of said channels remote from said chamber for connecting a rubber tube in operative relation thereto and means for admitting air under pressure to one of said channels intermediate the said valve therein and the said means at the end thereof remote from said chamber, said means for admitting air consisting of an air passage communicating with and at substantially right angles to said channel, a collapsible bulb operatively connected to the end of said passage remote from said channel, a port in the wall of said passage communicating with the atmosphere and a valve in said passage adapted to be rotated to selectively connect the said channel, the said port and the said bulb. 5 10 15 20
